US00D813908S

(12) **United States Design Patent** (10) Patent No.: **US D813,908 S**
(45) Date of Patent: **** Mar. 27, 2018**

(54) **CELLULAR PHONE WITH GRAPHICAL USER INTERFACE**

(71) Applicant: **LG ELECTRONICS INC.**, Seoul (KR)

(72) Inventors: **Jaehyeok Park**, Seoul (KR); **Jisoon Park**, Seoul (KR); **Hana Jeong**, Seoul (KR)

(73) Assignee: **LG ELECTRONICS INC.**, Seoul (KR)

(**) Term: **15 Years**

(21) Appl. No.: **35/501,328**

(22) Filed: **Feb. 2, 2016**

(80) **Hague Agreement Data**

Int. Filing Date: **Feb. 2, 2016**

Int. Reg. No.: **DM/089540**

Int. Reg. Date: **Feb. 2, 2016**

Int. Reg. Pub. Date: **Aug. 5, 2016**

(30) **Foreign Application Priority Data**

Aug. 5, 2015 (KR) 30-2015-0039665
